GUNNER'S CONTROL HANDLE FOR A FIRE CONTROL SYSTEM

Arthur T. Henshall, Baltimore, and Charles C. Tomlinson, Glen Burnie, Md., assignors, by mesne assignments, to the United States of America as represented by the Secretary of the Navy

Application May 11, 1954, Serial No. 429,141

7 Claims. (Cl. 89—41)

The present invention relates to a fire control system gunner's control handle and more particularly to a control handle which will pivot about a point located on a plane as a radius of a sphere would move about in a segment of the sphere and which will translate these rotary movements into rectangular coordinates.

The previously known fire control system gunner's control handles have been mounted in fixed and swinging gimbals from which azimuth and elevation movements were transmitted to the azimuth and elevation synchros. These prior existing control handles were complex to build and maintain and the constant flexing of the leads to the swinging gimbals reduced their expected life and required frequent repair.

The present invention overcomes the disadvantages of the prior known devices by the provision of a control handle which is small, light and inexpensive and all components of which are mounted on stationary structure.

An object of the present invention is the provision of a fire control system gunner's control handle which is inexpensive to manufacture, rugged in operation, and easy to maintain.

Another object of the invention is the provision of a gunner's control handle which eliminates all lead wire flexing.

Other objects and many of the attendant advantages of this invention will be readily appreciated as the same becomes better understood by reference to the following detailed description when considered in connection with the accompanying drawing wherein the figure shows a perspective view of a control handle and its associated signal pickoffs according to the present invention.

Referring more particularly to the drawing, the handle 11 is mounted on a shaft 12 which is affixed to the upper surface of a block 13. The block 13 is gimballed in the yoke 14 by means of transverse pin 15, the ends of which are received in the openings 16 in the arms 17 of the yoke. The handle 11 and the block 13 are thus capable of pivotal movement within the yoke about the pin as an axis. The base of the yoke 14 is affixed at its midpoint to one end of a shaft 18 the shank of which extends through and is journaled within a stationary bearing block 19. A sector gear 21 is secured to the free end of shaft 18 which protrudes from the bearing block. The bearing block 19 supports the handle assembly and the yoke affixed to the shaft 18 and permits pivotal movement of the handle and the yoke about the shaft 18 with the shaft as an axis of rotation. This pivotal movement of the handle is transmitted by the sector gear 21 to the gear train 22 (shown schematically in dotted lines) which drives the azimuth signal pickoff 23.

At the open end of the yoke 14, a flat cam 24 is secured to the side of block 13 in the plane of the handle 11. The edge of the cam 24 removed from the block 13 is curved in a vertical plane to form a flat cam surface 25 along which rides a cam follower 26. The follower 26 consists of a shaft 27 slidably mounted in stationary

2

bearing block 28 and spring-loaded so as to bear against surface 25 by means of compression spring 29 surrounding the shank of the shaft and compressed between one surface of the bearing block 28 and the collar 31. The free end of the shaft 27 is provided with a longitudinal rack 32 which meshes with gear train 33 (shown schematically in dotted lines) to drive the elevation signal pickoff 34.

In operation, a transverse movement of the handle 11

10 rotates shaft 18 in the same direction within the bearing block 19 and imparts movement to sector gear 21 which activates the azimuth signal pickoff 23 through gear train 22. A forward or rearward movement of the handle rotates cam 24 about the pin 15 causing the spring-loaded

15 follower 26 to retract or project respectively, thus moving rack 32 and activating the elevation signal pickoff 34 by means of gear train 33.

By the proper choice of sizes and numbers of gears in the gear trains 22 and 33 respectively, the movements

20 of the sector gear 21 and the rack 32 may be magnified and/or reversed to provide azimuth and elevation pick-off signals of the proper magnitude and direction. To provide functional linearity between the handle and the elevation rack, the cam must be mounted in the plane of

25 the centerline of the handle, the cam follower 26 should be a point contact follower, and the cam surface 25 may be an Archimedean spiral. To avoid azimuth cross talk on the elevation output, it is necessary that the point of contact between the cam surface and the cam follower

30 be on the axis of rotation of the yoke 14.

Obviously many modifications and variations of the present invention are possible in the light of the above teachings. It is therefore to be understood that within the scope of the appended claims the invention may be practiced otherwise than as specifically described.

What is claimed is:

1. A fire control system gunner's control handle comprising first and second rigid supports; a yoke having a pair of arms and a cylindrical shank journaled within said first support for axial rotation therein; gear means on said shank; a handle assembly gimballed between the arms of said yoke, said handle assembly including a handle and a cam mounted in the plane of the centerline of said handle; a cam follower mounted for reciprocating movement in said second support and bearing against said cam on the axis of rotation of said yoke; and rack means on said follower; whereby transverse movement of the handle rotates the cylindrical shank and its gear means for activating an azimuth signal pickoff, and forward or rearward movement of the handle rotates the cam causing longitudinal movement of the follower and its rack means for activating an elevation signal pickoff.

2. A fire control system gunner's control handle comprising a yoke having a pair of arms and a shank; gear means on said shank; a handle assembly gimballed between the arms of said yoke, said handle assembly including a handle and a cam mounted in the plane of the centerline of said handle; a cam follower bearing against said cam on the axis of rotation of said yoke; and rack means on said follower; whereby transverse movement of the handle rotates the shank and its gear means for activating an azimuth signal pickoff, and forward or rearward movement of the handle rotates the cam causing longitudinal movement of the follower and its rack means for activating an elevation signal pickoff.

3. A fire control system gunner's control handle comprising first and second rigid supports; a yoke having a pair of arms and a cylindrical shank journaled within said first support for axial rotation therein; gear means on said shank; a handle assembly gimballed between the arms of said yoke, said handle assembly including a han-

3

idle and a cam having a curved cam surface mounted in the plane of the centerline of said handle; a spring-loaded point-contact cam follower mounted for reciprocating movement in said second support and bearing against said curved surface on the axis of rotation of said yoke; and rack means on said follower; whereby transverse movement of the handle rotates the cylindrical shank and its gear means for activating an azimuth signal pickoff, and forward or rearward movement of the handle rotates the cam causing longitudinal movement of the follower and its rack means for activating an elevation signal pickoff.

4. A fire control system gunner's control handle comprising a yoke having a pair of arms and a shank; gear means on said shank; a handle assembly gimbaled between the arms of said yoke; said handle assembly including a handle and a cam having a curved cam surface mounted in the plane of the centerline of said handle; a spring-loaded point-contact cam follower bearing against said curved surface on the axis of rotation of said yoke; and rack means on said follower; whereby transverse movement of the handle rotates the shank and its gear means for activating an azimuth signal pickoff, and forward or rearward movement of the handle rotates the cam causing longitudinal movement of the follower and its rack means for activating an elevation signal pickoff.

5. A gunner's control handle for a fire control system comprising a shaft capable of axial rotation; a handle assembly pivotally mounted on one end of said shaft; said assembly including a handle and a cam mounted in the plane of the centerline of said handle; a cam follower capable of reciprocating movement bearing against said cam on the axis of rotation of said shaft; means on said shaft for activating an azimuth signal pickoff in response to transverse movement of the handle; and means on said follower for activating an elevation signal pickoff in response to forward or rearward movement of the handle.

6. A gunner's control handle for a fire control system comprising first and second rigid supports; a shaft journalled in said first support for axial rotation therein;

4

a handle assembly transversely pivoted at one end of said shaft, said assembly including a handle and a flat cam having a curved surface mounted in the plane of the centerline of said handle; a point-contact cam follower mounted for reciprocating movement in said second support and bearing against said curved surface on the axis of rotation of said shaft; means on said shaft for activating an azimuth signal pickoff in response to transverse movement of the handle; and means on said follower for activating an elevation signal pickoff in response to forward or rearward movement of the handle.

7. A control handle for a fire control system comprising first and second rigid supports; a yoke having a pair of arms and a cylindrical shank journalled within said first support for axial rotation therein; a handle assembly pivoted transversely between the arms of said yoke; said assembly including a handle and a flat cam having a curved surface mounted in the plane of the centerline of said handle; a point-contact cam follower mounted for reciprocating movement in said second support and spring-biased to maintain contact with said curved surface on the axis of rotation of said yoke; means on said shank for activating an azimuth signal pickoff in response to transverse movement of the handle; and means on said follower for activating an elevation signal pickoff in response to forward or rearward movement of the handle.
